RADIANT FOR A GAS HEATER OR SIMILAR ARTICLE

Bernard Paul Lunkwicz, Dallas, Tex., assignor to Dearborn Stove Company, Dallas, Tex., a corporation of Texas

Application May 27, 1957, Serial No. 46,367

Term of patent 14 years

(Cl. D81—10)

Fig. 1

Fig. 2

Fig. 3

Fig. 4

Fig. 5

Figure 1 is a top plan view of a radiant for a gas heater embodying my new design;

Figure 2 is a side elevational view thereof, the side not shown being the same as the side shown;

Figure 3 is a front elevational view of the radiant;

Figure 4 is a rear elevational view thereof; and

Figure 5 is a bottom plan view of the radiant.

I claim:

The ornamental design for a radiant for a gas heater or similar article, substantially as shown and described.
